YIELDABLE TICKET HOLDER

Pierre H. Meyer, Mount Vernon, N. Y.

Application February 4, 1938, Serial No. 188,693

2 Claims. (Cl. 248—33)

This invention relates to ticket holders for supporting price tickets, cards or the like, in conjunction with merchandise arranged and displayed on a counter, shelf or other support; and the object 5 of the invention is to provide a device of this kind employing a ticket or card supporting plate and a spring arm detachably coupled with the plate in several positions to provide different arrangements of the plate with respect to said arm; a further object being to provide means for detachably 10 mounting the arm in connection with a suitable support, said means comprising a base plate having a socket in which one end of the arm is adapted to be placed, said base plate having means 15 for detachably or otherwise securing the same to a supporting surface; a still further object being to provide means for supporting the arm in an angular position with respect to a support; and with these and other objects in view, the invention 20 consists in a unit of the class described involving three detachably coupled parts which is constructed as more fully hereinafter described and claimed.

Fig. 1 is a perspective view showing one form 25 of the unit and indicating the flexibility of the spring arm or standard thereof.

Fig. 2 is a view similar to Fig. 1 showing only a part of the construction and with a part in different position.

30 Fig. 3 is a side edge view of the device shown in Fig. 1 showing another method of mounting the ticket supporting plate in connection with the arm.

Fig. 4 is a view similar to Fig. 3 showing another 35 form of construction.

Fig. 5 is a partial section on the line 5—5 of Fig. 1 on an enlarged scale and with parts of the construction broken away, and

Fig. 6 is a perspective view of the arm or stand- 40 ard detached.

In practise I provide a card or ticket supporting unit consisting of three detachably related parts, comprising a base 10, a standard or arm 11, and a ticket supporting plate 12. These parts 45 may be detached for packing, shipment, and storage; and assembled in several different manners to produce different displaying effects of the ticket supporting plate 12 with respect to the base or a suitable support.

50 The base 10 in the construction shown, comprises an oblong rectangular plate 13 having a series of apertures 14 by means of which the plate 13 may be fixedly secured to a suitable support by nails, screws, or the like. In some cases, I may 55 utilize a key-hole aperture 15 for detachably sup-

porting the plate in connection with a headed screw 16, especially when one edge of the base is arranged adjacent a support which would prevent rotation of the base on the screw 16. One end of the base includes an integral upwardly projecting flange 17 to which is secured a metal strip or strap 18 by welding or in any other desired manner; the strap having an offset portion 19 which forms between it and the flange 17, a socket 20 for receiving one end of the standard or arm 11. The strap 18 or the offset portion 19 thereof includes an integral extension 19a which extends onto the upper surface of the plate 13 and is welded thereto so as to reinforce the socket 20 and give rigidity thereto.

The arm 11 is frictionally held and supported in the socket 20. This arm is preferably composed of spring steel to give free flexibility or resiliency thereto so that if the plate 12 be accidentally hit or engaged, the arm will simply 20 vibrate or flex in the manner indicated in dotted lines as seen at 11a in Fig. 1 of the drawing by virtue of the spring properties thereof. The upper end 21 of the arm is offset with respect to the longitudinal plane of said arm in order to support the plate 12 in an angular position. The plate 12 has inturned upper and lower flanges 12a, 12b, which retain a card or ticket such as 22, Fig. 1 of the drawing, against displacement from the upper and lower edges; whereas the side edges 30 12c are flexed forwardly a sufficient degree to flex a card 22 and prevent lateral accidental displacement thereof, while at the same time facilitating the forceable removal of the card or ticket 22 through either side of the plate as in other de- 35 vices of this kind.

Secured to the rear surface of the plate 12 is a strap 23, similar to the strap 18, and which is welded in position. This strap has an offset central portion 24, similar to the offset 19, except that the reinforcement 19a is mounted. The portion 24 forms a channel 25 between the same and the body portion of the plate 12 in which the end 21 of the arm 11 is adapted to be frictionally placed so that the plate 12 is firmly retained 40 against displacement from the arm but can be forceably removed therefrom.

In the construction shown in Fig. 1 of the drawing, the strap 23 is disposed adjacent the lower edge of the plate 12. However, in Fig. 2 of the 50 drawing, I have shown another method of mounting the plate 12 upon the angular end 21 of the arm 11 by simply inverting the plate to arrange the flange 12b at the top thereof instead of at the bottom. In this construction, it will appear 55

that the plate 12 will extend over the base plate 13; whereas in Fig. 1, the plate 12 extends at the rear edge of the base plate 13.

In Fig. 3 of the drawing, I have shown another 5 possible arrangement of the parts; and in this figure, the arm 11 has been reversed in the socket 20 so that the plate 12 mounted on the arm as seen in Fig. 1, assumes a position extending over the base plate 13 rather than rearwardly thereof.

10 Both ends of the arm 11 are of the same width and thickness so that it would be possible to support the end 21 within the socket 20, and a ticket supporting plate 12 might be supported in any position upon the straight end portion of 15 the arm if this type of display or mounting should be desirable. However, in Fig. 4 of the drawing, I have shown a modification which consists in providing an arm 11b having two offset end portions 26, 26a so that the arm 11b may be extended over the base plate 13 or may be extended away from this base plate by reversing the position of the arm 11b. The ticket supporting plate 12 may be supported on either side of the end 26 of the arm as indicated in full and dotted lines 20 in Fig. 4; and in the dotted line position, may be attached in the manner taught in Fig. 2.

From the foregoing, it will appear that the invention consists primarily in providing two plate portions or parts, 10, 12, each having a socket 30 for receiving the other part 11—11b which is detachable with respect to the sockets of the plate parts 10 and 12. The plate part 10 forms the support or base of the resulting device; whereas the plate 12 forms the ticket or card holder. In 35 this connection, it will be understood that the size and construction of the plate 12 may be varied to suit different types and kinds of cards employed, the only essential feature being the provision of a suitable socket on the ticket or card supporting member for frictionally receiving one end of the standard or arm 11—11b.

It will of course be understood that the arm 11 may be of different lengths to vary the height of

the part 12 with respect to a supporting surface; and being composed of spring material, this arm may be shaped to any desired form or contour intermediate the ends thereof to produce a pre-determined effect. It will also be apparent that my invention is not limited to the specific arrangement of the sockets herein disclosed, as these are illustrative of a few uses of the invention. 5

Having fully described my invention, what I 10 claim as new and desire to secure by Letters Patent, is:

1. In a ticket holding device of the character described, a supporting base comprising sheet metal plate having an integral upstanding flange 15 at one edge thereof, an offset strap secured to the surface of the flange adjacent said plate to form between the flange and the offset portion of the strap a socket for the reception of a ticket holder supporting arm, said offset strap including an angular part extending onto the upper surface 20 of said base plate, and secured thereto to reinforce the upstanding socket portion of said base.

2. In a ticket holding device of the character described, a supporting base comprising sheet metal plate having an integral upstanding flange at one edge thereof, an offset strap secured to the surface of the flange adjacent said plate to form between the flange and the offset portion of the strap a socket for the reception of a ticket holder supporting arm, said offset strap including an angular part extending onto the upper surface of said base plate, and secured thereto to reinforce the upstanding socket portion of said base, said arm comprising an elongated strip of spring material having an angular end portion offset in the plane of said arm, a ticket supporting plate, and an offset strap centrally of one edge portion of the rear surface of said plate for the reception of one end of the spring arm in yieldably supporting said plate in connection with said base. 30 35 40
